(57) **CLAIM**

The ornamental design for a motor vehicle, toy vehicle replica and/or other replica, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a motor vehicle, toy vehicle replica and/or other replica;

FIG. 2 is a front view thereof;

FIG. 3 is a rear view thereof;

FIG. 4 is a right side view thereof, the left side being a mirror image of the right side; and,

FIG. 5 is a top plan view thereof.

The broken line showing of the motor vehicle, toy vehicle replica and/or other replica forms no part of the claimed design.

1 Claim, 5 Drawing Sheets

UNITED STATES PATENT AND TRADEMARK OFFICE
CERTIFICATE OF CORRECTION

PATENT NO. : D1,021,690 S
APPLICATION NO. : 29/780831
DATED : April 9, 2024
INVENTOR(S) : Woosung Chung

Page 1 of 6

It is certified that error appears in the above-identified patent and that said Letters Patent is hereby corrected as shown below:

On the Title Page

Replace the illustrative print figure, with the corrected FIG. 1, as shown on the attached drawing sheet.

In the Drawings

Replace drawings sheets 1 thru 5 with the attached drawing sheets, showing the corrected FIGS. 1-5.

Signed and Sealed this
Seventeenth Day of December, 2024

Derrick Brent
Acting Director of the United States Patent and Trademark Office
